UNITED STATES PATENT OFFICE.

LOUIS KOVACS, OF THROOP, PENNSYLVANIA.

AEROPLANE SAFETY DEVICE.

1,346,214.

Specification of Letters Patent. Patented July 13, 1920.

Application filed February 28, 1920. Serial No. 361,991.

To all whom it may concern:

Be it known that I, LOUIS KOVACS, citizen of the United States, and resident of Throop, in the county of Lackawanna and State of Pennsylvania, have invented certain new and useful Improvements in Aeroplane Safety Devices, of which the following is a specification.

This invention relates to emergency de-10 scensional devices for aeroplanes and especially to devices for enabling the plane to descend slowly to the ground in case it is, for any reason, disabled.

The object of this invention is the pro-15 vision of a lever controlled collapsible device, designed to be automatically unfolded into operative position in any emergency for making a safe descent.

A further object of this invention is the 20 provision of a light, safety descensional device, normally collapsed, which does not interfere with the ordinary operation of the plane, and which offers little wind resistance.

25 It is well known, that ordinarily, if the engine of the aeroplane should stop while the plane is in the air, the operator may vol-plane or glide to the earth. However, should a wing be damaged or give way, or 30 should the operator be injured or otherwise unable to guide the machine to the ground, serious injury is certain to occur. It is my purpose to provide a surface resistance to the air for retarding the fall, advantage being taken also of the initial horizontal velocity of the plane in the operation of my device.

For the accomplishment of the aforesaid and other objects, I employ the device shown 40 in its preferred form in the accompanying drawings, in which,

Figure 1 is a side view of my invention as it appears in its operative position. Fig. 2 is a side view and partial section of a portion of the mechanism used for opening my device automatically. Fig. 3 is a front view and partial section of the same. Fig. 4 is a plan view of the controlling lever which sets the operating mechanism in motion. Fig. 5 is a plan view of my invention as it appears when opened to its operative position. Fig. 6 is a vertical section of the same on line 6—6 of Fig. 5.

In the practical embodiment of my invention, a pair of auxiliary wings 1 and 2, of strong silk or other suitable fabric 10, is

supported by ribs 3 which are spaced apart at suitable intervals throughout the length of said wings. The cross sectional shape of said wings is preferably that shown in Fig. 6, the upper part 4 being cylindrical to increase to some extent, the air pressure therein, with the aid of the constricted opening 5 at the lower part thereof. Rods 6 suitably attached to the body of the plane at 7, pass through ribs 3 whereby wings 1 and 2 are supported from the fuselage 8, said wings being connected by a series of cross bars 9 suitably attached to said ribs 3.

In the normal inoperative position of 70 wings 1 and 2, ribs 3 assume the position shown by the dash and dot lines in Fig. 1, fabric 10 lying in folds between said ribs. For normally maintaining said wings in the collapsed position, grooved pulleys 12 and 75 13 on shafts 11 and 14 respectively passing through the body of fuselage 8, are designed to hold line 15 normally stationary thereon.

Mechanism is provided for quickly drawing wings 1 and 2 from their collapsed position to their extended position as shown by Figs. 1 and 5, this being accomplished by the rotation of shaft 14 and pulley 13 thereon, whereby line 15, which is attached to the first one of ribs 3, draws said rib toward 80 said shaft 14 until it can go no farther due to the tension on the fabric 10. Gear 16 on shaft 14 is driven from a series of gears 17 attached to spring casings as 18, which casings can be rotated by springs as 19. For 90 winding up springs 19, the ends of shafts 24 on which gears 17 are loosely mounted are squared at 20 to receive a crank key as 22, ratchet wheels as 21 being mounted on said shafts 24 near the ends thereof.

95 A casing 23 supports the various shafts 24, pawls as 25 being pivotally secured at 26 to said casing, said pawls being urged into engagement with said ratchet wheels by means of springs 27 attached at one end 28 100 to casing 23.

Shaft 14 is ordinarily prevented from rotating by bifurcated arm 29 pivotally supported from casing 23 by bracket 30 at 31, secured at one end to crank lever 32 at 33 105 and at its other end to hollow cylinder 34, slidably mounted on shaft 14. Pins 35 on shaft 14 normally engage notches 36 in cylinder 34, which cylinder is prevented from rotating by arm 29, whereby said shaft 14 110 is also prevented from rotating. For disengaging cylinder 34 from pins 35, crank lever

32 is connected at toggle joint 37 to link 38 which is pivoted at one end 39 to bracket 40 of casing 23, a spring 41 acting to assist in the disengagement. A hand wheel 42 is placed on shaft 14 for bringing wings 1 and 2 back to their collapsed position manually, at the convenience of the operator.

If an accident should occur while the plane is in the air, to prevent the operator 10 from descending in the usual manner, as, if the engine should be stalled or a wing should break, or the operator should become faint, crank lever 32 is pulled, loosening toggle joint 37, whereby the distance between points 39 and 33 is shortened, and arm 29 rotated about pivot 31 to disengage cylinder 34 from pins 35, aided by spring 41. Shaft 14 is now free to rotate due to the action of springs 19, through gears 16 and 17, and turns pulley 13 to operate line 15 for expanding wings 1 and 2 to their most extended position. A large air resisting surface is thereby suddenly presented, the sudden descent of the plane being checked, and the plane is allowed to reach the ground slowly.

What I claim is:

1. In combination with an aeroplane, a pair of collapsible wings, one arranged on each side of said aeroplane, each of said wings being adapted for extension in the direction of the length of said aeroplane, a series of spring motors, gears on said motors, a shaft operatively connected to said wings, a gear on said shaft operatively engaging said motor gears, and a control lever for causing said shaft to rotate for extending said wings.

2. A device of the character described comprising a pair of collapsible wings, each in cross section approximately a semi-ellipse, said wings being each provided with an auxiliary top compartment of circular cross section, longitudinally disposed rods attached to the fuselage of an aeroplane 40 supporting said wings from the inner sides of said wings, and means for extending said wings.

3. In a device of the character described, in combination with an aeroplane, a pair of collapsible wings, each in cross section approximately a semi-ellipse, each provided with an auxiliary top compartment of circular cross section, and each comprising a series of ribs and a flexible cover for said ribs, rods fastened to said aeroplane passing through that side of said ribs nearest the aeroplane, a pair of pulleys, shafts support-

ing said pulleys passing through said plane, means for driving one of said shafts, and means normally preventing the rotation of 60 said last mentioned shaft.

4. In a device of the character described, in combination with an aeroplane, a pair of collapsible wings disposed on each side of said aeroplane, each comprising a series of 65 ribs whose cross sectional shape is approximately a semi-ellipse having an auxiliary top portion of circular cross section and a flexible cover for said ribs, longitudinally disposed guides for said wings attached to the fuselage and passing through said ribs on the side adjacent to said fuselage, controllable means for quickly unfolding said wings into operative position, and means for normally preventing the unfolding of said wings. 75

5. In a device of the character described, a pair of collapsible wings, each in cross section approximately a semi-ellipse, said wings being each provided with an auxiliary top compartment of circular cross section, 80 supporting guides for one side of each of said wings, a shaft, means for rotating said shaft comprising a spring capable of being wound up, a casing for said spring, and a gear attached to said casing operatively connected to said shaft, means for normally preventing rotation of said shaft, a pulley on said shaft, a second pulley disposed rearwardly of said wings, and a line attached to a wing passing around said pulleys for extending said wings on the rotation of said shaft. 85

6. In a device of the character described, a pair of collapsible wings each comprising a series of ribs and a flexible cover for said ribs, supporting guide rods passing through said ribs, a shaft, means for rotating said shaft, means for normally preventing the rotation of said shaft, comprising pins in said shaft, a hollow cylinder engaging said pins, a lever secured to said cylinder, and a bracket preventing the rotation of said lever, a crank lever for disengaging said cylinder from said pins for allowing said shaft to be rotated, a pulley on said shaft, a second pulley, and a line passing around said pulleys attached to the forward end of one of said wings for unfolding said wing to its extended position when said cylinder is disengaged from said pins. 95 100 105

Signed at Throop, in the county of Lackawanna and State of Pennsylvania this 25th day of February, A. D. 1920.

LOUIS KOVACS.
